COLLAPSIBLE TUBE

Alois Brossette, Solingen, Germany

Application October 5, 1937, Serial No. 167,437
In Germany July 2, 1936

15 Claims. (Cl. 93—94)

My invention relates to a collapsible tube such as is ordinarily used as a container of plasti-
5 cal, liquid or pulverized materials, e. g. for cos-
metical purposes, and is particularly concerned
with improvements in the structure of the tube
and in the process of manufacturing it.

An object of my invention is to produce such
tubes of an organic cellulose-containing sheet
material, particularly of a transparent sheet
10 of cellulose derivatives. Another object is an
improved process of manufacture resulting in a
tube of an organic material which is not inferior
to, and may compete with tubes of sheet metal
and satisfies all reasonable requirements.

15 My invention is based on the fact that, in any
tube produced by winding up a strip of organic
sheet material and by gluing the superimposed
plies together by an intermediate layer of bind-
ing material, the intermediate layer has a func-
20 tion which has not been recognized prior to my
invention. I have found that the nature of the
intermediate layer is controlling on the qualities
of the product. Moreover I have found it neces-
25 sary to subject the sheet of a cellulose material
to a preparatory treatment thus enabling the
sheet to properly cooperate with the intermedia-
te layer. The primary consideration for the
choice of the intermediate layer is the necessity
30 that such layer should not only act as a glue but
should also have additional functions, particu-
larly the function as an insulating medium ren-
dering the tube moisture-proof.

I have found that the tubes produced in ac-
cordance with my invention are entirely free
35 from the shortcomings of the tubes of a cellu-
lose material produced in accordance with known
processes.

The improved process comprises preferably
40 three steps, to-wit coating the cellulose sheet
material with a moisture-proof layer, coating
such layer with a gum or glue and winding up
the sheet material so treated to form a cylind-
rical body from which the collapsible tube is
45 produced in a known manner.

For the purpose of my invention I prefer to
use a sheet material consisting of a cellulose
ester such as acetyl cellulose or nitro-cellulose.
I may also use other cellulose derivatives such
50 as viscose. Such sheet materials or foils are
available on the market. Very frequently they
are coated with a varnish comprising a solution
of nitro-cellulose or cellulose or the like.

Further objects of my invention will appear
from the description of a preferred embodiment
55 thereof following hereinafter with reference to

the drawing in which I have shown a tube which
may be manufactured by my improved process.

The tube shown on the drawing comprises the
cylindrical body A consisting of superimposed
plies formed by winding up a strip of sheet ma-
5 terial on a mandrel, the plies being glued to-
gether so as to constitute a pliable sleeve. The
lower end of the tube thus formed is closed in
any suitable manner, e. g. by pressing the op-
posed walls of the tube upon each other and by 10
folding them over, as indicated at B. The upper
end C is pressed in suitable dies to form a mouth
piece provided with threads D to receive a
threaded cover, not shown.

My invention is primarily concerned with the 15
first step of this process, i. e. the winding of the
strip of material upon a mandrel to form the
tube body A.

In producing this body I may start with a strip
of acetyl cellulose and with a liquid produced 20
by mixing collodium elasticum, traumaticin and
benzyl alcohol. Traumaticin is a solution of
gutta-percha in a solvent comprising trichlorae-
thylen and an acetone-like medium such as
drawin which is adapted to partly dissolve acetyl 25
cellulose. Drawin is an acetone solution which
is mixed with cheaper solvents. This liquid is
applied to one or both sides of the sheet material
in a thin layer, e. g. by means of rollers. The
liquid has the effect of superficially dissolving the 30
sheet material thus rendering the surface there-
of porous whereby the gutta-percha contained
in the liquid is enabled to penetrate into the
pores. Then the solvent is removed, e. g. vapor-
35 ized in vacuum. As a result, the gutta-percha
will constitute a thin coat which is intimately
interlocked with the sheet material. The col-
lodium elasticum contained in the liquid will
40 form a film of nitro-cellulose. The benzyl al-
cohol serves solely the function of producing a
mixture between traumaticin and collodium
elasticum and disappears when the solvent is
vaporized. After the vaporization, the sheet ma-
45 terial of acetyl cellulose is coated and intimately
interlocked with a layer of gutta-percha consti-
tuting a moisture-proof material. This layer of
gutta-percha is coated in its turn with a layer
50 of a nitro-cellulose varnish. The coated sheet
material so produced is now in a condition to be
provided on its coated face with a layer of a
suitable adhesive of glue, containing e. g. a
polymerization product, such as polyacrylacid-
55 ester or gutta-percha. I prefer to dissolve this
adhesive in a volatile solvent containing a small
percentage of a liquid adapted to superficially

dissolve the layer of varnish. Suitable solvents are, for instance, chloroform, sulfuric or ethylic ether, acetone, gasoline, benzol or benzene, alcohol and the like. Therefore, when the adhesive 5 is applied to the coated sheet material, the coating of varnish thereon will be superficially dissolved and rendered porous enabling the adhesive to penetrate into the pores of the layer of varnish.

Before the adhesive layer is dried, the sheet 10 material is wound up on a suitable mandrel. In this operation the adhesive on one ply will contact with the cellulose material of the superimposed ply and will superficially dissolve the cellulose material thereof. As a result, the adhesive 15 will intimately interlock with the superimposed layer of cellulose material and will thus bind the two plies effectively one to another.

I may admix a pigment either to the liquid 20 consisting of collodium elasticum, traumaticin and benzyl alcohol or to the adhesive, if it is desired to produce an opaque tube. Such a pigment may be a pulverized aluminum or a suitable color. The admixture of a pulverized aluminum 25 has the additional advantage of enhancing the resistivity against moisture.

In another form of my improved process the first step comprises superficially dissolving the sheet material of acetyl cellulose, e. g. by use of a suitable solvent such as acetone. Then a 30 solution of gutta-percha is applied to the sheet material to produce the moisture-proof layer. This layer is dried and is then coated with a suitable varnish. After the coat of varnish has been dried, it is superficially dissolved again and 35 then provided with a coat of adhesive. Before the adhesive is dry, the sheet material is wound up upon the mandrel and is then permitted to dry.

Also the layer of pigment may be added in a 40 separate step.

The cellulose sheet material in its commercial form is usually coated with a layer of varnish which is easier soluble in the solvents mentioned above than the cellulose material and is therefore particularly adapted to intimately bind the moisture-proof layer to the sheet material.

While I have described two preferred embodiments of my invention, I wish it to be clearly understood that my invention is capable of numerous modifications within the scope of the 50 appended claims.

Thus I may use other moisture-proof materials than gutta-percha to coat the sheet material, e. g. rubber. Also, other cellulose-containing 55 sheet materials than transparent sheets may be used, e. g. paper. Moreover anyone skilled in the art will readily appreciate that a great multiplicity of various solvents may be selected depending on the properties of the sheet material, of the moisture-proof coat and of the adhesive.

What I claim is:

1. Process for the production of tubes for the reception of plastic materials consisting in treating a sheet of a transparent cellulose derivative 60 with a solution of collodium elasticum, traumaticin and benzyl alcohol, coating said treated sheet with a material substantially different from and with superficial solvent properties for the cellulose derivative material, said coating serving as an intermediate layer having adhesive, isolating 65 and insulating properties and winding said sheet onto a cylinder to form a tube, said coating holding the wound sheet together.

2. Process for the production of tubes for the 70 reception of plastic materials consisting in coating a sheet of a transparent cellulose derivative

with a varnish, treating said sheet with a solution of collodium elasticum, traumaticin and benzyl alcohol, coating said treated sheet with a material substantially different from, and with superficial solvent properties for, the cellulose derivative material, said coating serving as an intermediate layer having adhesive, isolating and insulating properties winding the sheet onto a cylinder to form a tube, said adhesive coating holding the wound sheet together. 10

3. Process for the production of tubes for the reception of plastic materials consisting in treating a sheet of a transparent cellulose derivative with a solution of collodium elasticum, traumaticin and benzyl alcohol, coating said treated sheet 15 with a material substantially different from, and with superficial solvent properties for, the cellulose derivative material, said coating containing a pigment carrier and serving as an intermediate layer having adhesive, isolating and insulating properties, winding the sheet onto a cylinder to form a tube, said adhesive coating holding the wound sheet together. 20

4. A process for the production of tubes for the reception of plastic materials consisting in coating a sheet of a transparent cellulose derivative with a varnish, treating said sheet with a solution of collodium elasticum, traumaticin and benzyl alcohol, coating said treated sheet with a material substantially different from, and with superficial 30 solvent properties for, the cellulose derivative material, said coating containing a pigment carrier, and serving as an intermediate layer having adhesive, isolating and insulating properties, winding the sheet onto a cylinder to form a tube, said adhesive coating holding the wound sheet together. 35

5. A process for the production of tubes for the reception of plastic materials consisting in treating a sheet of a transparent cellulose derivative with a solution of collodium elasticum, traumaticin and benzyl alcohol, coating said treated sheet with a material substantially different from, and with superficial solvent properties for, the cellulose derivative material, said coating containing aluminium powder and serving as an intermediate layer having adhesive, isolating and insulating properties, winding the sheet onto a cylinder to form a tube, said coating holding the wound sheet together. 40

6. A process for the production of tubes for the reception of plastic material consisting in coating a sheet of a transparent cellulose derivative with a varnish, treating said sheet with a solution of collodium elasticum, traumaticin and benzyl alcohol, coating said treated sheet with a material substantially different from, and with superficial solvent properties for, the cellulose derivative material, said coating containing aluminium powder and serving as an intermediate 55 layer having adhesive, isolating and insulating properties, winding said sheet onto a cylinder to form a tube, said adhesive coating holding the wound sheet together.

7. In a process for the production of tubes for the reception of plastic materials, the steps which comprise treating a sheet of a cellulose derivative with a moisture-proof material which is dissolved in a liquid having a solvent action with respect to the cellulose derivative, coating said 70 treated sheet with an adhesive with superficial solvent properties for the treated cellulose derivative sheet, and winding said sheet onto a mandrel to form a tube the walls of which consist of a plurality of superimposed layers of said 75

wound sheet with intermediate layers of said moisture-proof material and said adhesive between the said superimposed layers.

8. In a process for the production of tubes for the reception of plastic materials, the steps which comprise treating a sheet of a cellulose derivative with a moisture-proof material of the group comprising gutta-percha and rubber which is dissolved in a liquid having a solvent action with respect to the cellulose derivative, coating said treated sheet with an adhesive with superficial solvent properties for the treated cellulose derivative sheet, and winding said sheet onto a mandrel to form a tube the walls of which consist of a plurality of superimposed layers of said wound sheet with intermediate layers of said moisture-proof material and said adhesive between the said superimposed layers.

9. In a process for the production of tubes for the reception of plastic materials, the steps which comprise treating a sheet of a cellulose derivative with a moisture-proof material which is dissolved in a liquid having a solvent action with respect to the cellulose derivative, coating said treated sheet with an adhesive with superficial solvent properties for the treated cellulose derivative sheet, of the group comprising solutions of polymerisation products and gutta-percha, and winding said sheet onto a mandrel to form a tube the walls of which consist of a plurality of superimposed layers of said wound sheet with intermediate layers of said moisture-proof material and said adhesive between the said superimposed layers.

10. In a process for the production of tubes for the reception of plastic materials, the steps which comprise treating a sheet of a cellulose derivative with a moisture-proof material which is dissolved in a liquid having a solvent action with respect to the cellulose derivative, coating said treated sheet with polyacrylacidester dissolved in a volatile solvent containing a small percentage of a liquid adapted to dissolve the surface of the treated cellulose derivative sheet, and winding said sheet onto a mandrel to form a tube the walls of which consist of a plurality of superimposed layers of said wound sheet with intermediate layers of said moisture-proof material and said polyacrylacidester between the said superimposed layers.

11. In a process for the production of tubes for the reception of plastic materials, the steps which comprise treating a sheet of a cellulose derivative with a moisture-proof material of the group comprising gutta-percha and rubber which is dissolved in a liquid having a solvent action with respect to the cellulose derivative, coating said treated sheet with an adhesive with superficial solvent properties for the treated cellulose derivative sheet, of the group comprising solutions of polymerisation products and gutta-percha, and winding said sheet onto a mandrel to form a tube the walls of which consist of a plurality of superimposed layers of said wound sheet with intermediate layers of said moisture-proof material and said adhesive between the said superimposed layers.

12. In a process for the production of tubes for the reception of plastic materials, the steps which comprise treating a sheet of a cellulose derivative with a moisture-proof material which is dissolved in a liquid having a solvent action with respect to the cellulose derivative, coating said treated sheet with an adhesive with superficial solvent properties for the treated cellulose derivative sheet, and winding said sheet onto a mandrel before said adhesive layer is dried, to form a tube the walls of which consist of a plurality of superimposed layers of said wound sheet with intermediate layers of said moisture-proof material and said adhesive between the said superimposed layers.

13. In a process for the production of tubes for the reception of plastic materials, the steps which comprise superficially dissolving a sheet of a cellulose derivative, treating said sheet with a moisture-proof material which is dissolved in a liquid having a solvent action with respect to the cellulose derivative, coating said treated sheet with an adhesive with superficial solvent properties for the treated cellulose derivative sheet, and winding said sheet onto a mandrel to form a tube the walls of which consist of a plurality of superimposed layers of said wound sheet with intermediate layers of said moisture-proof material and said adhesive between the said superimposed layers.

14. In a process for the production of tubes for the reception of plastic materials, the steps which comprise superficially dissolving a sheet of a cellulose derivative, treating said sheet with a moisture-proof material which is dissolved in a liquid having a solvent action with respect to the cellulose derivative, drying and coating the treated sheet with a varnish, drying said varnish coating, superficially redissolving the varnish coating and coating said treated sheet with an adhesive with superficial solvent properties for the treated cellulose derivative sheet, and winding said sheet onto a mandrel to form a tube the walls of which consist of a plurality of superimposed layers of said wound sheet with intermediate layers of said moisture-proof material and said adhesive between the said superimposed layers.

15. In a process of producing tubes for the reception of plastic material from commercial cellulose sheet material having a varnish coating on its surface, the steps which comprise treating a sheet of a cellulose derivative with a moisture-proof material which is dissolved in a liquid having a solvent action with respect to the said varnish coating, coating said treated sheet with an adhesive with superficial solvent properties for the treated cellulose derivative sheet, and winding said sheet onto a mandrel to form a tube the walls of which consist of a plurality of superimposed layers of said wound sheet with intermediate layers of said moisture-proof material and said adhesive between the said superimposed layers.

ALOIS BROSSETTE. 65
